(57) **CLAIM**

We claim the ornamental design for a thermoelectric cooling device, as shown and described.

DESCRIPTION

FIG. 1 is a front perspective view of a thermoelectric cooling device;

FIG. 2 is a side view of the thermoelectric cooling device of FIG. 1;

FIG. 3 is a front view of the thermoelectric cooling device of FIG. 1;

FIG. 4 is a top view of the thermoelectric cooling device of FIG. 1; and,

FIG. 5 is a bottom view of the thermoelectric cooling device of FIG. 1.

The broken lines shown in FIGS. 1, 2 and 5 illustrate portions of the thermoelectric cooling device that forms no part of the claimed design.
